UNITED STATES PATENT OFFICE.

JOHN B. WHITNEY, OF NEW YORK, N. Y.

DESIGN FOR KEY-HOLE ESCUTCHEONS.

Specification forming part of Design No. 6,365, dated January 21, 1873.

To all whom it may concern:

Be it known that I, JOHN B. WHITNEY, of the city, county, and State of New York, have invented a new and original Design for a Key-Hole Escutcheon, of which the following is a specification:

The accompanying engraving fully represents my new design.

This invention relates to a new form of escutcheon for key-holes of doors, and to a new ornamentation of the same; also to a new design for the key-hole plate or shield.

The escutcheon, which has two key-holes cut through it, as shown, or but one, if desired, is of mixtilinear outline, as shown, and orna-

mented about the lower key-hole and around the screw-holes by appropriate scrolls. The key-hole plate or shield is of the peculiar form shown, is fastened in place by a pivot having a star-shaped head, and otherwise decorated by an ornamental scroll, as shown.

I claim as my invention—

1. The design for the escutcheon, as shown.
2. The design for the key-hole plate or shield, as shown.

JOHN B. WHITNEY.
